(57) **CLAIM**

The ornamental design for a hood for an automatic hair washer, as shown and described.

DESCRIPTION

FIG. 1 is a front view of a hood for an automatic hair washer in accordance with my new design;

FIG. 2 is a back view thereof;

FIG. 3 is a right side view thereof;

FIG. 4 is a left side view thereof;

FIG. 5 is a top view thereof;

FIG. 6 is a bottom view thereof;

FIG. 7 is a perspective view showing the design in place in an automatic washer; and,

FIG. 8 is a perspective view showing the design without the environment shown in FIG. 7.

The broken line showing of the automatic washer is for illustrative purposes only and forms no part of the claimed design.
